UNITED STATES PATENT OFFICE.

ARTHUR NIHLEN, OF NEW YORK, N. Y., ASSIGNOR OF ONE-HALF TO PETER NELSON,
OF YONKERS, NEW YORK.

MITERING-CLAMP.

1,169,671.

Specification of Letters Patent.

Patented Jan. 25, 1916.

Application filed September 4, 1913. Serial No. 788,127.

To all whom it may concern:

Be it known that I, ARTHUR NIHLEN, a citizen of the United States, residing at New York, in the county of New York, State of New York, have invented certain new and useful Improvements in Mitering-Clamps; and I do hereby declare the following to be a full, clear, and exact description of the invention, such as will enable others skilled in the art to which it appertains to make and use the same.

This invention relates to improvements in clamps and particularly to wood working clamps for gluing together the mitered ends of molding.

The principal object of the invention is to provide a novelly constructed clamp which is particularly adapted for clamping mitered joints.

Another object is to provide a device of this character which is adjustable to force the parts of the mitered joint together, and also to engage and rigidly hold the parts in such position.

Other objects and advantages will be apparent from the following description when taken in connection with the accompanying drawings.

In the drawings: Figure 1 is a perspective view of the clamp in use. Fig. 2 is a side elevation of a clamp made in accordance with my invention. Fig. 3 is a top plan view, a mitered joint being shown in dotted lines. Fig. 4 is a vertical transverse sectional view on the line 4—4 of Fig. 2. Fig. 5 is a horizontal section on the line 5—5 of Fig. 2, and Fig. 6 is a vertical longitudinal sectional view on the line 6—6 of Fig. 3.

Referring particularly to the accompanying drawings, 10 represents an elongated frame which is formed with a central longitudinal slot 11, the undersides of the side portions of the frame being formed with the ledges 12. At one end of the frame is an upstanding standard or lug 13, this lug having a longitudinal oppositely tapered bore 14 formed therethrough. Disposed in this bore is a pin 14' through which is formed a transverse threaded opening 15' receiving the screw shaft 15. The screw is thus permitted a vertical locking movement with the pin 14' as the axis. At the opposite end of the frame is an obliquely arranged standard 16, the rear side of which is pro-

vided with a strengthening rib 17. A 55 clamping member 18 is disposed on this standard 16 and has the inwardly extending members 19 which interlock with lateral ribs 20, on the standard and slide vertically thereon, this jaw being disposed over the 60 end of the frame, and extending transversely of the frame at an angle of approximately 45 degrees. This clamping member is disposed to slide vertically on the standard 16 and is movable thereon by 65 means of a screw 21 which is disposed through a threaded boss 22 carried on the upper end of said standard and is rotatably secured to the clamping member. The upper end of this screw has a handle 25 for rotating the screw. Disposed against the ledges 12 from the underside of the frame, and extending across the opening 11, is a plate 26, 70 this plate having secured to its upper side a vertical standard 26'. The before mentioned screw 15 has its inner end rotatably mounted in a plate 37 adjustably mounted on the rear side of the standard 26', and its opposite end provided with a handle 28 so that by rotating the screw the standard can 75 be moved longitudinally in the slot of the frame toward and away from the member 18. The plate 37 is provided with a vertical elongated slot 38' which receives therethrough a clamping screw 39, this screw being carried by the standard 26'. Vertically 80 slideable on the standard 26', is a clamp member 29. This clamp member is in the form of a block, its forward face being arranged transversely and obliquely of the 85 frame at an angle of 45 degrees. The upper end of the standard 26' has a forwardly extending boss 33 directed toward the boss 22 and provided with a vertical threaded opening receiving a screw 30. The lower end of 90 this screw is rotatably secured in the upper side of the block 29 and has on its upper end a handle 31. Thus by turning the screw 30, the block 29 can be moved up and down on the standard 26' away from and toward the 95 frame. At the same time the screw 15 is arranged to move the standard 26 together with the block 29 toward or away from the other member 18. On the upper face at each 100 end of the member 10 and on the plate 26 are the teeth 38.

When it is desired to glue the mitered ends of two moldings together one of the

pieces is placed on the frame 10 and against the face on the standard 16 so as to extend parallel thereto. The clamping member 18 is then moved downwardly by means of the screw 21 until the teeth 38 adjacent the standard 16 penetrate the bottom face of the molding. This piece of molding will thus be held in position by the coaction of the teeth 38 and the clamp 18, the other piece of 10 molding is then placed on the frame 10 so that it extends across the plate 26 and in contact with the standard 26' so as to contact with the standard 26' so as to extend parallel to the adjacent face of said standard. The clamping member 29 is then moved downwardly by means of the screw 30 and causes the teeth 38 on the plate 26 to bite into the molding at which time the molding will be held in position by the 15 action of the said teeth 38 on the plate 26 and the clamping member 29. The glue is then applied to the mitered ends of the molding and the screw 15 operated to move the molding which is supported on the plate 25 26 toward the piece of molding which is clamped by the member 18 until the mitered faces contact at which time the screw 15 is moved slightly further to press the said faces together in which position the pieces 30 of molding are held until the glue hardens, of course it is to be realized that the machine will operate with moldings of various types, the type illustrated in the drawing merely being one of the said types, and inasmuch as the widths will vary it is desirable 35 to apply the pressure from the screw 15 at different points on the standard 26', at a low point for a narrow molding and at a high point for a wide molding. It is for this reason that the plate 37 is made ad-

justable on the standard 26' in the manner previously described.

By raising and lowering the plate 37 the screw 15 can be rocked with the pin 14' so that the point of pressure of the screw can be applied at the point desired. Thus the screw 15 forces the parts of the joint together and the jaws 18 and 29 hold the parts against movement in any direction.

When it is desired to apply pressure to 50 various points on the molding, it will only be necessary to loosen the screw 39 and move the plate 37 upwardly on the standard 26', at which time the end of the screw 15 will be raised and the screw rock on its pivot 14'. The slot 37' is provided for convenience of 55 insertion of the screw head 15. The head of this screw 15 is rounded so that it will not bind against the plate 37 when the plate is moved upwardly.

60 What is claimed is:—

In a miter clamp, a frame, a standard formed on one end thereof, a clamping member slidably mounted on said standard, a plate slidably mounted on said frame, a standard formed on said plate, a clamping member on said standard, means for transmitting force to the last mentioned standard to move the same toward the first mentioned standard, and means for adjusting the said first mentioned means in such manner that the point of application of the force to the second mentioned standard may be varied at the will of the operator.

70 In testimony whereof, I affix my signature, in the presence of two witnesses.

ARTHUR NIHLEN.
